United States Patent Office

Des. 219,124
Patented Nov. 10, 1970

219,124

PRESSURIZED DISPENSING CONTAINER

Norman Gortz, 11151 Coventry Place, Santa Ana, Calif.
92700, and Michael B. Maccarone, 1793 Gillman Ave.,
Irvine, Calif. 92664

Filed Nov. 13, 1969, Ser. No. 20,069

Term of patent 14 years

Int. Cl. D9—01

U.S. Cl. D9—8

FIG. 3.

FIG. 4.

FIG. 1.

FIG. 2.

FIG. 1 is a front elevational view of a pressurized dispensing container embodying our new design;

FIG. 2 is an elevational view looking from the right of FIG. 1;

FIG. 3 is a top plan view; and

FIG. 4 is a bottom plan view thereof.

We claim:

The ornamental design for a pressurized dispensing container, substantially as shown.
